(57) CLAIM

The ornamental design for a lamp clamp as shown and described.

DESCRIPTION

FIG. 1 is a perspective view of a lamp clamp;

FIG. 2 is a front view of the lamp clamp;

FIG. 3 is a rear view of the lamp clamp;

FIG. 4 is a left side of the lamp clamp;

FIG. 5 is a right side of the lamp clamp;

FIG. 6 is a top view of the lamp clamp;

FIG. 7 is a bottom view of the lamp clamp; and,

FIG. 8 is another perspective view of the lamp clamp.

The broken lines in the drawings depict portions of the lamp clamp that form no part of the claimed design.
